(57) **CLAIM**

The ornamental design for a bath bomb mold, as shown and described.

DESCRIPTION

FIG. 1 is a perspective view of a bath bomb mold showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded perspective view; and,

FIG. 10 is an exploded perspective view with bath bomb mold shown in an alternate configuration.

The broken lines in the drawings depict portions of the bath bomb mold that form no part of the claimed design.
